CONTROL FOR HYDRAULIC MACHINES

James K. Douglas, Shorewood, Wis., assignor to
The Oilgear Company, Milwaukee, Wis., a corporation of Wisconsin

Application March 12, 1937, Serial No. 130,427

20 Claims. (Cl. 60—52)

This invention relates to hydraulic machines capable of maintaining a holding pressure substantially constant, such as the machine shown in my copending application Serial No. 28,068 5 of which this application is a continuation as to matters common to both applications and which has since matured into Patent No. 2,080,810.

The machine shown in the above application includes a variable displacement pump for supplying motive liquid to a hydraulic motor to operate the same and a control which permits the pump to deliver liquid to the motor at a predetermined maximum rate until the motor meets sufficient resistance to cause pump pressure 15 sure to rise to a predetermined maximum and then the control reduces pump displacement until the pump is delivering just sufficient liquid to maintain that maximum pressure constant. The control may be adjusted to vary the maximum 20 pressure but a different maximum pressure cannot be maintained without adjustment of the control.

The present invention has as an object to provide a hydraulic machine which is capable of 25 maintaining any one of a plurality of predetermined pressures constant.

Another object is to provide means whereby any one of a plurality of predetermined maximum pressures may be selected at a point remote from 30 the pump and its control.

Another object is to provide a reversible pump which is capable of maintaining any one of a plurality of predetermined pressures constant.

Other objects and particular advantages of the 35 invention will appear from the following description of the hydraulic machine shown schematically in the accompanying drawings in which the views are as follows:

Fig. 1 is a circuit diagram of a hydraulic press 40 to which the invention has been applied.

Fig. 2 is a schematic drawing showing the mechanism which controls the operation of the pump shown in Fig. 1.

Fig. 3 is a view showing the selector valve in 45 a different characteristic position.

Fig. 4 is a section through the selector valve taken on the line 4—4 of Fig. 2.

Fig. 5 is a view showing an adjustable resistance valve which may be substituted for the 50 selector valve and associated resistance valves shown in Figs. 1 to 4.

The press shown in Fig. 1 includes a ram 1, which is fitted in a stationary cylinder 2 and connected at its lower end to a movable press 55 head or platen 3, and two pistons 4 and 4^a which

are fitted, respectively, in stationary cylinders 5 and 5^a and connected by rods 6 and 6^a to platen 3 to move it toward and from a stationary press head 7.

Cylinder 5 has its upper end connected by a 5 channel 8 to the upper end of cylinder 5^a and by a channel 9 to one port of a pump 10 and its lower end connected by a channel 11 to the lower end of cylinder 5^a and by a channel 12 to the other port of pump 10 so that, when pump 10 10 delivers liquid into channel 12, pistons 4 and 4^a will be moved upward simultaneously and move platen 3 and ram 1 upward and, when pump 10 delivers liquid into channel 9, pistons 4 and 4^a, platen 3 and ram 1 will move downward. 15

Ram cylinder 2 is connected through a surge valve 13 and a channel 14 to a surge tank 15 which contains a supply of liquid and is connected by an overflow channel 16 to a reservoir 17 which is ordinarily formed in the base of pump 10. 20

Surge valve 13 has not been shown in detail for the reason that such valves are well known and in extensive commercial use. It is deemed sufficient to state that it has one of its ports connected to channel 9 by a channel 18, another of 25 its ports connected to channel 12 by a channel 19 and that it operates as follows:

When pump 10 delivers liquid into channel 12 to raise pistons 4 and 4^a, pressure extends through channel 19 and shifts surge valve 13 to a position 30 in which cylinder 2 is open to channel 14 so that, as platen 3 and ram 1 are raised by pistons 4 and 4^a, ram 1 may eject liquid from cylinder 2 through valve 13 and channel 14 into surge tank 15. If the liquid ejected from cylinder 2 into 35 surge tank 15 raises the level of the liquid therein above the entrance to drain channel 16, liquid will flow through channel 16 into reservoir 17.

When pump 10 delivers liquid into channel 9 and has liquid returned to it through channel 40 12, either gravity or liquid supplied to the upper ends of cylinders 5 and 5^a at a low pressure by pump 10 will cause ram 1, platen 3 and pistons 4 and 4^a to move downward until further downward movement thereof is arrested by head 7 or 45 by work arranged between it and platen 3.

As ram 1 moves downward, liquid will flow from tank 15 through channel 14 and valve 13 to cylinder 1 and keep it filled. Also, if ram 1 and pistons 4 and 4^a move downward by gravity 50 and tend to cause a deficiency of liquid in channel 9 and the upper ends of cylinders 5 and 5^a, such deficiency will be made up by liquid which flows from tank 15 into channel 9 through a check valve 20 which permits liquid to flow in 55

that direction but prevents it from flowing in the opposite direction.

When downward movement of platen 3 is arrested by head 7 or by the work, pressure will rise in channels 9 and 18 until it is high enough to cause liquid to flow through channel 18 and shift valve 13 to a position in which cylinder 2 is closed to channel 14 and open to channel 18 so that the upper end of ram 1 is exposed to pump pressure. Then platen 3 is urged downward by a force equal to the product of the pump pressure and the combined areas of ram 1 and pistons 4 and 4'.

The movement of platen 3 may be reversed by reversing the pump or by means of a valve to reverse the flow of liquid in channels 9 and 12. For the purpose of illustration, pump 10 has been shown as being reversible by operating a rod 21 which is slideable horizontally in a stationary bearing 22 and urged toward the right by a spring 23.

Rod 21 has a roller 24 arranged upon the right end thereof and held by spring 23 in contact with the beveled face of a cam 25 fixed upon the upper end of a rod 26 which is slideable vertically through at least one guide 27 and extends downward through an arm 28 carried by platen 3. The lower end of rod 26 is connected to one end of a control lever 29 which is pivoted intermediate its ends to a stationary bracket 30.

When the free end of lever 29 is depressed to a position below a central or neutral position as shown in full lines, cam 25 will hold rod 21 in a position to cause pump 10 to deliver liquid into channel 9 and thereby cause platen 3 to descend.

When the free end of lever 29 is raised to a neutral position as indicated by dotted lines at 31, cam 25 will permit spring 23 to shift rod 21 to a position to cause the displacement of pump 10 to be reduced to zero so that the press remains idle.

When the free end of lever 29 is moved to a position above neutral as indicated by dotted lines at 32, cam 25 will permit spring 23 to shift rod 21 to a position to cause pump 10 to deliver liquid into channel 12 and thereby cause platen 3 to rise.

Arm 28 is provided in order that upward movement of platen 3 may be arrested at a predetermined point. To this end, a collar 33 is fixed upon rod 26 in such a position that, as platen 3 approaches the point at which its upward movement is to be arrested, arm 28 will engage collar 33 and raise it and rod 26 until cam 25 has shifted rod 21 far enough to reduce pump displacement to zero at which time further upward movement of platen 3 ceases.

If platen 3 should then tend to descend due to leakage or other causes, a spring 34 arranged around rod 26 between guide 27 and collar 33 would move rod 26 and cam 25 downward until spring 23 had shifted rod 21 far enough to cause pump 10 to deliver just sufficient liquid into channel 12 to hold up the platen.

Pump 10 has been shown in Fig. 2 as being of the rolling piston type fully illustrated and described in Patent No. 2,074,068. It is deemed sufficient to state that the pump has its cylinders 65 and pistons arranged radially in a cylinder barrel 38 which rotates upon a central valve shaft or pintle 40 through which liquid flows to and from the cylinders.

Cylinder barrel 38 is arranged inside a thrust member or slide block 41 which is closely fitted in the casing 42 of pump 10. Slide block 41 is provided with an inner circular reaction surface 43 which engages the outer ends of heads of the pistons and causes the pistons to reciprocate in the cylinders whenever the cylinder barrel is ro-

tated and the axis of the reaction surface is offset from the axis of the cylinder barrel. The stroke of the pistons and consequently the volumetric delivery of the pump is proportional to the distance that the axis of the reaction surface is offset from the axis of the cylinder barrel.

If the cylinder barrel 38 is rotated in a counter-clockwise direction as viewed in Fig. 2, pump 10 will deliver liquid into channel 9 when the axis of reaction surface 43 is offset toward the left from the axis of pintle 40 as shown, and it will deliver liquid into channel 12 when the axis of reaction surface 43 is offset toward the right from the axis of pintle 40.

Slide block 41 is adapted to be moved toward the right by a hydraulic servo-motor consisting of a stationary cylinder 44 and a piston 45 which is fitted in cylinder 44, connected to slide block 41 and operated by liquid supplied to cylinder 44 under the control of mechanism to be presently described.

Slide block 41 may be urged toward the left by springs as shown in Patent No. 2,080,810, particularly if the movement of platen 3 is to be reversed by reversing the flow of liquid in channels 9 and 12 by means of a reversing valve. For the purpose of illustration however, pump 10 has been shown as being reversible and as having slide block 41 urged toward the left by a hydraulic servo-motor consisting of a stationary cylinder 46 and a piston 47 which is fitted in cylinder 46 and connected to slide block 41 by a stem 48.

Liquid for operating servo-motor 46-47 is supplied by a gear pump 50 which is ordinarily driven in unison with cylinder barrel 38 and arranged within pump casing 42 according to the usual practice and as shown in Patent No. 2,074,068. Gear pump 50 draws its supply of liquid from reservoir 17 through a channel 51 and discharges it into a channel 52 having connected thereto a low pressure relief valve 53 through which all liquid discharged by the gear pump in excess of requirements is exhausted and which enables the gear pump to maintain a low pressure in channel 52.

Operation of servo-motor 46-47 is controlled by a follow-up valve which, in practice, is of the rotary type but, in order to illustrate the operation of both the follow-up valve and the servo-motor in a single view, the follow-up valve has been shown as being of the reciprocating type.

As shown, cylinder 46 is provided upon its outer end with a head 54 of substantial thickness having a bore 55 extending therethrough. A bore 56 is formed in piston 47 and in stem 48 in axial alignment with bore 55, and a plunger type follow-up valve 57 is fitted in bores 55 and 56 to reciprocate therein.

Gear pump discharge channel 52 communicates with an annular groove 58 which is formed in the wall of bore 55 and to which gear pump 50 continuously supplies liquid at a constant pressure as determined by the resistance of valve 53. Liquid which may escape from groove 58 outward along valve 57 is collected in an annular groove 59 which is formed in the wall of bore 55 and discharges into reservoir 17 as by means of a drain channel 60.

Valve 57 is provided with an axial passage 63 which is closed at each of its ends and is at all times in communication with groove 58 through a plurality of radial ducts 64 formed in valve 57. Passage 63 is connected near its inner end by a plurality of radial ducts 65 to an annular supply groove 66 which is formed in the peripheral sur-

face of valve 57. Consequently, groove 66 is continuously supplied with liquid from gear pump 50.

An annular drain groove 67 is formed in the peripheral surface of valve 57 a short distance from supply groove 66 and connected to the inner end of bore 56 by a plurality of ducts 68 which extend from groove 67 through the end of valve 57. A plurality of openings 69 formed in the inner part of stem 48 permit liquid discharged through groove 67 and ducts 68 into the inner end of bore 56 to escape therefrom into pump casing 42 from which this liquid may escape into drain channel 60.

When piston 47 and valve 57 are in their normal relative positions, grooves 66 and 67 are arranged upon opposite sides of an annular groove 70 which is formed in the wall of bore 56 in piston 47 and communicates with the interior of cylinder 46 through a plurality of ducts 71 formed in piston 47.

The width of groove 70 is ordinarily equal to the distance between grooves 66 and 67. That is, in the normal positions of valve 57 and piston 47, the edges of groove 70 are ordinarily in alignment, respectively, with the adjacent edges of grooves 66 and 67 so that there is no communication between groove 70 and groove 66 or groove 67 but a slight movement of valve 57 in one direction or the other will open groove 70 to groove 66 or to groove 67.

Movement of valve 57 toward the left opens supply groove 66 to groove 70 and thereby permits liquid to flow therethrough and through ducts 71 to the interior of cylinder 46 and move piston 47 and slide block 41 toward the left against the resistance of piston 45 provided the pressure in cylinder 44 is not too high.

When piston 47 has moved exactly the same distance that the valve was moved, groove 70 passes out of registry with groove 66, thereby stopping any further movement of the piston by cutting off the supply of driving liquid and trapping the liquid then contained in cylinder 46. The liquid trapped in the cylinder 46 then holds piston 47 and slide block 41 stationary until valve 57 is again shifted or until the pressure in cylinder 44 becomes high enough to move piston 45 and slide block 41 toward the right against the resistance offered by piston 47.

In order that slide block 41 may be moved toward the right when valve 57 is stationary, a relief valve 72 is connected between cylinder 46 and drain channel 60 and adjusted to open at a pressure a few pounds higher than the pressure at which gear pump relief valve 53 opens so that, when the pressure in cylinder 44 becomes high enough to cause slide block 41 to be shifted toward the right as will be presently explained, piston 47 may eject liquid from cylinder 46 through relief valve 72.

Movement of valve 57 toward the right opens drain groove 67 to groove 70 so that liquid may escape therethrough and through ducts 68 from the interior of cylinder 46 and permit piston 45 to move slide block 41 and piston 47 toward the right. When piston 47 has moved toward the right the same distance that valve 57 was moved, groove 70 passes out of registry with groove 67, thereby stopping any further movement of the piston by cutting off the escape of liquid and trapping the liquid then remaining in cylinder 46. The liquid trapped in cylinder 46 then holds piston 47 and slide block 41 stationary until valve 57 is again shifted or until the pressure in cylinder 44 becomes high enough to move piston 45 and slide block 41 toward the right against the resistance offered by piston 47.

Valve 57 is shifted through the medium of rod 21 which is connected thereto so that, when the free end of control lever 29 is depressed, cam 25 will rise and shift rod 21 and valve 57 toward the left and, when the free end of lever 29 is raised, cam 25 will descend and permit spring 23 to shift rod 21 and valve 57 toward the right.

Piston 45 is urged toward the right by liquid supplied to cylinder 44 from gear pump 50 when the pressure developed by pump 10 is below a predetermined value and by liquid supplied to cylinder 44 from pump 10 when the pressure developed by pump 10 is above a predetermined value. The effective pressure area of piston 45 is smaller than the effective pressure area of piston 47 so that, when cylinder 44 is being supplied with liquid from gear pump 50 and valve 57 is shifted toward the left to admit liquid from gear pump 50 into cylinder 46, the force exerted by the liquid upon piston 47 will be greater than the force exerted by the liquid upon piston 45 so that slide block 41 will be shifted toward the left and, when valve 57 is shifted toward the right to open cylinder 46 to drain, the force exerted by gear pump liquid upon piston 45 will be ample to shift slide block 41 toward the right. When liquid is supplied to cylinder 44 from pump 10 at a predetermined pressure which is higher than gear pump pressure, the force exerted by this liquid upon piston 45 is ample to shift slide block 41 toward the right regardless of whether valve 57 is open or closed.

The delivery of liquid from pump 10 to cylinder 44 is under the control of a pressure responsive control valve 75 which is closely fitted in a bore 76 formed in a control unit casing 77. Bore 76 is connected at its lower end to pressure channel 9 by a channel 78 so that the lower end of valve 75 is exposed at all times to the pressure created by pump 10.

Valve 75 controls communication between the lower part of bore 76 and a port 79 which is formed in the wall of bore 76 intermediate the ends thereof, the lower end of valve 75 being provided with one or more notches 80 for the purpose of throttling the flow of liquid into port 79.

Valve 75 is fixed at its upper end to a piston 81 closely fitted in a counterbore 82 which is considerably larger in diameter than bore 76 and is closed at its upper end by a cover plate 83 attached to the top of casing 77.

Piston 81 controls communication between counterbore 82 and an annular port 84 which is formed in the wall thereof, a plurality of notches 85 being formed in the upper edge of piston 81 to throttle the flow of liquid between counterbore 82 and port 84.

If pump 10 were employed to deliver liquid in but one direction so that the only function of piston 45 would be to vary pump displacement, port 84 would be connected to drain. However, in order that piston 45 may also function to reverse the direction of pump delivery, port 84 has been shown as being connected by a channel 86 to gear pump supply channel 52 so that gear pump 50 may deliver liquid to cylinder 44 to effect reversal of pump 10 as will be presently explained.

Notches 80 and 85 are preferably so arranged that the vertical distance between them is equal to the vertical distance between the bottom of port 79 and the upper edge of port 84 so that, when control valve 75 has been raised until the

bottom of notch 88 is even with the bottom of port 79, the bottom of notches 85 will be even with the upper edge of port 84. Then, a very slight movement of control valve 75 in either direction will open either port 79 to pressure channel 9 or counterbore 82 to port 84.

Valve 75 is urged upward or toward open position by the pump pressure in the lower end of bore 76, and it is also urged upward by the pressure prevailing in an annular groove 87 arranged around counterbore 82 at its junction with bore 76. Groove 87 is connected by a channel 88 to a channel 89 which connects port 79 to cylinder 44 so that the pressure in groove 87 is ordinarily the same as pressure in cylinder 44.

Valve 75 is urged downward or toward closed position by a helical compression spring 91 arranged in counterbore 82 between piston 81 and a plunger 82 which extends through cover plate 83 and is closely fitted therein. The upper end of plunger 82 engages a piston 93 which is closely fitted in a cylinder 94 shown as being attached to cover plate 83. Piston 93 is adapted to be urged downward by liquid supplied to cylinder 94 at any one of a plurality of pre-selected pressures as will be presently explained.

The arrangement is such that valve 75 is held closed until pump pressure rises to a value great enough to cause the liquid in bore 76 to exert upon the lower end of valve 75 a force greater than the force exerted upon piston 93 by spring 91 at which time valve 75 will be moved upward and permit liquid to flow from pressure channel 9 through channel 78, bore 76, port 79 and channel 89 to cylinder 44 and move piston 45 and slide block 41 toward the right to reduce the displacement of pump 10 until pump 10 is delivering just sufficient liquid to maintain pump pressure at that value.

The pump pressure at which valve 75 will open is thus proportional to the pressure in cylinder 94 provided the pressure in cylinder 94 is great enough to compress spring 91. In order to vary the pump pressure at which valve 75 opens, the pressure in cylinder 94 is varied by mechanism to be presently described. If the pressure in cylinder 94 is lower than the pressure required to compress spring 91, piston 93 will stall against the head of cylinder 94 and then the pump pressure required to open valve 75 will be the pressure required to compress spring 91.

Due primarily to the mechanism which controls the pressure in cylinder 94, there would be a small amount of lag in the operation of valve 75 if plunger 82 acted directly upon piston 81. By interposing spring 91 between plunger 82 and piston 81, piston 81 is free to move at any instant without waiting for a corresponding movement of piston 93, and valve 75 opens substantially instantaneously in response to pump pressure reaching a predetermined maximum.

When valve 75 opens, liquid flows through channel 89 to cylinder 44 and shifts slide block 41 toward the right as previously explained. In order to prevent this liquid from moving the slide block so fast that the momentum thereof would cause it to move too far and thus cause hunting, a choke 95 is arranged in channel 89 to limit the rate at which liquid may enter cylinder 94 and thereby limit the rate at which the slide block may move.

The flow of liquid through channel 89 is also restricted by a throttle valve 96 which offers a small resistance to the flow of liquid past it so that the pressure in channel 88 and groove 87 is

higher than the pressure in cylinder 44 when liquid is flowing through channel 89 to cylinder 44.

In order that gear pump 50 may deliver liquid to cylinder 44 to operate piston 45 and in order that liquid may be exhausted from counterbore 82 by the upward movement of piston 81 after port 84 is closed, a channel 97 has one of its ends connected to counterbore 82 and its other end connected through a check valve 98 to a channel 99 which is connected to channel 89.

In order that liquid may be expelled from cylinder 44 by piston 45 when slide block 41 is shifted toward the left to increase pump displacement, a resistance valve 100 and a bleeder choke 101 are connected between channels 97 and 89 in parallel with check valve 98 and with each other. Check valve 98 permits liquid to flow freely from channel 97 into channel 89 but prevents it from flowing from channel 89 into channel 97 except through resistance valve 100 or choke 101.

Choke 101 prevents liquid from flowing therethrough except at a very limited rate so that, when slide block 41 is moved toward the left and causes piston 45 to expel liquid from cylinder 44, nearly all of this liquid must pass through resistance valve 100 which is adjusted to open at a low pressure.

Resistance valve 100 resists the flow of liquid therethrough and thereby resists movement of slide block 41 toward the left and also causes the pressure in channel 89 to be higher than the pressure in channel 97 which at this time is open to gear pump supply channel 52. Moving slide block 41 toward the left increases pump delivery which ordinarily results in an increase in pump pressure. Since valve 75 is closed at this time so that there is no flow of liquid through channel 89, the pressure prevailing in channel 89 can extend past throttle valve 96 into groove 87 and act upon the lower end of piston 81, thereby assisting pump pressure to raise valve 75 which is thus caused to start upward just before pump pressure reaches a predetermined maximum.

As valve 75 moves upward, notches 85 throttle the flow of liquid from counterbore 82 to port 84 and thereby cause the pressure to rise in channel 97 until the difference between the pressures in channels 97 and 89 is less than the pressure required to open valve 100 which will then close so that the liquid expelled from cylinder 44 by piston 45 during further movement of slide block 41 must pass at a slow rate through bleeder choke 101. The result is that slide block 41 is moved rapidly during the first part of its movement and is decelerated during the last part of its movement so that it cannot overrun, thereby preventing hunting.

When pump pressure is caused to rise substantially instantly, as by platen 3 stalling, the inertia of slide block 41 will prevent pump displacement from being reduced quickly enough to prevent pump pressure from exceeding the predetermined maximum. In order to relieve the pump under such a condition, the apparatus is provided with a high pressure relief valve 105 and, in order that the pressure at which relief valve 105 opens shall bear a definite relation to the pressure at which pump displacement is reduced, the operation of relief valve 105 is placed under the control of valve 75.

As shown, relief valve 105 is closely fitted in a bore 106 which is formed in casing 77 and connected intermediate its ends to bore 76 by a channel 107. The lower end of valve 105 normally engages an annular valve seat 108 formed in the

lower end of bore 106 around a relief channel 109 which has been shown in Fig. 2 as being connected to drain channel 60 but, in practice, relief channel 109 extends through casing 77 and discharges into the sump of pump 10.

Relief valve 105 is fastened at its upper end to a piston 111 which is considerably larger in diameter than valve 105 and fitted in a counterbore 112 formed in valve casing 77 concentric with bore 106. Counterbore 112 is closed at its upper end by cover plate 83 and connected at a point below piston 111 to port 79 by a channel 113 having a choke 114 arranged therein.

A spring 115, arranged in counterbore 112 between piston 111 and cover plate 83, urges piston 111 downward and normally holds valve 105 in contact with valve seat 108 to close communication between channel 107 and relief channel 109. In order that operation of piston 111 may not be impeded by entrapped gas or liquid, drain channel 60 has been shown in Fig. 2 as being connected to counterbore 112 above piston 111.

When valve 75 opens and permits liquid from pump 10 to enter port 79, pressure will extend through channel 113 and choke 114 to the lower end of counterbore 112 and act upon the lower face of piston 111. When the pressure in the lower end of counterbore 112 becomes high enough to overcome the resistance of spring 115, piston 111 will move upward and raise valve 105 away from seat 108, thereby permitting pump 10 to discharge through channels 9, 78 and 107 into relief channel 109. Since relief valve 105 is not subjected to pump pressure but is opened by pressure which acts upon piston 111 only after valve 75 opens, it will open at a pressure which is always the same number of pounds higher than the pressure at which valve 75 opens regardless of the amount of pressure required to open valve 75.

As previously explained, the pressure prevailing in cylinder 94 determines the pump pressure required to open valve 75. Cylinder 94 is connected through a channel 120, an orifice choke 121, a channel 122, a second orifice choke 123 and a channel 124 to gear pump supply channel 52 so that gear pump 50 may supply liquid under pressure to cylinder 94.

In order to vary and to limit the pressure in cylinder 94, liquid may be permitted to escape from channel 122 through either a free channel, or through any one of a plurality of resistance valves as shown in Figs. 1 and 2, or through a single adjustable resistance valve as shown in Fig. 5.

Channel 122 has been shown in Figs. 1 and 2 as being connected by a channel 125 to the inlet of a selector valve 126 through which it may be connected to any one of a plurality of resistance valves or to drain. For the purpose of illustration, the apparatus has been shown as having four resistance valves 127, 128, 129 and 130 arranged in a casing 131 having formed therein a bore 132 in which selector valve 126 is closely fitted to rotate therein.

As best shown in Fig. 4, channel 125 communicates with an annular groove 133 which is formed in the peripheral surface of valve 126 in a plane below the plane of the resistance valves. A duct 134 extends radially inward from groove 133 into communication with a vertical duct 135 extending upward in valve 126 and communicating with a radial duct 136 which is arranged in the plane of the resistance valves and communicates with a port 137 formed in the peripheral surface

of valve 126. It is to be understood that vertical duct 135 is closed below groove 133 and above duct 136.

Resistance valves 127, 128, 129 and 130 are adjusted to open at different pressures and have the inlets thereof open to bore 132 so that the resistance valves are controlled by selector valve 126. The outlets of the resistance valves are connected to each other as by means of ducts 138, 139 and 140, and the outlet of resistance valve 130 is connected by a duct 141 to a drain channel 142 which communicates with bore 132 and discharges into reservoir 17 as by being connected to drain channel 60.

For the purpose of illustration, the selector valve unit has been shown in Fig. 4 as having its casing 131 closed at its upper end by a removable head 143 and valve 126 as being provided with a stem 144 which extends through head 143 and has fixed thereon a handle 145 by means of which valve 126 may be rotated.

In order that selector valve 126 may be turned promptly to and stopped exactly in each of its six operative positions, handle 145 may have a pointer 146 fixed thereto in alinement with the center of port 137 and head 143 may be provided with six markers 147 one of which is arranged directly above drain channel 142, one of which is arranged directly above the inlet of each of resistance valves 127, 128, 129 and 130, and one of which is arranged midway between channel 142 and the inlet of resistance valve 127.

The arrangement is such that, when handle 145 is turned until pointer 146 registers with the marker above resistance valve 129 so that port 137 registers with the inlet of resistance valve 129 as shown in Figs. 2 and 4, liquid from gear pump supply channel 52 may flow through channel 124, choke 123, channels 122 and 125, groove 133, ducts 134, 135 and 136, port 137, resistance valve 129 and ducts 140 and 141 into drain channel 142.

Choke 123 limits the flow of liquid therethrough and thereby enables gear pump 50 to maintain in channel 52 a constant pressure equal to the resistance of relief valve 53. Resistance valve 129 resists the flow of liquid therethrough and thereby causes pressure to be created in port 137. This pressure will extend through ducts 136, 135 and 134, groove 133, channels 125 and 122, choke 121 and channel 120 to cylinder 94 and act upon piston 93 so that the pressure required to open valve 75 is determined by the pressure required to open resistance valve 129.

If handle 145 should be turned until port 137 registered with the inlet of any one of the other three resistance valves, valve 75 would open at a different pressure for the reason that resistance valves 127, 128, 129 and 130 open at different pressures.

If handle 145 should be turned until port 137 registered with channel 142 as shown in Fig. 1, the liquid passing through choke 123 could escape freely into drain channel 142 so that the pressure in cylinder 94 would be reduced substantially to zero with the result that the pressure required to open valve 75 would be determined by the initial tension of spring 91.

If handle 145 should be turned until pointer 146 registered with the marker 147 arranged midway between drain channel 142 and resistance valve 127, port 137 would be blocked as shown in Fig. 3, and no liquid could escape through valve 126. Consequently, gear pump pressure would extend through channel 124, choke 123, channel 75

122, choke 121 and channel 120 to cylinder 94 and act upon piston 93 so that the pressure required to open valve 75 would be determined by the resistance of relief valve 53.

8 It is thus apparent that any one of a plurality of predetermined maximum pump pressures may be selected by simply turning valve 126 which may be arranged remote from the pump at any convenient point. With the structure shown, 10 any one of six maximum pressures may be selected, namely, a low maximum pressure determined by the resistance of spring 91, a high maximum pressure determined by the resistance of relief valve 53, or any one of four intermediate maximum pressures determined by the resistances of valves 127, 128, 129 and 130 each of which may be individually adjusted.

Instead of varying the pressure in cylinder 94 by means of a plurality of resistance valves as 20 shown in Figs. 1 to 4, it may be varied by means of a single adjustable resistance valve such as the valve shown in Fig. 5. This valve has its casing 150 closed at one end by a head 151, connected intermediate its ends to drain channel 25 60, and its other end provided with an inlet 152 which is controlled by a valve 153 and connected to channel 125.

Valve 153 is urged against its seat by a spring 154 arranged within casing 150 between two 30 spring retainers 155 and 156 one of which engages valve 153 and the other of which engages an adjusting screw 157 threaded through head 151.

Screw 157 is adapted to be rotated by a handle 35 35 which is fixed upon the outer end thereof and provided with a pointer 159 to register with suitable graduations arranged upon head 151 but not shown in the drawings.

The characteristics of spring 154 and the pitch 40 40 of screw 157 are preferably such that less than a complete revolution of screw 157 is required to vary the tension of spring 154 between zero and a predetermined maximum which is great enough to hold valve 153 closed against a pressure at least as great as the gear pump pressure.

45 When the tension of spring 154 is substantially zero, little if any pressure is required to open valve 153 and liquid may flow substantially freely from channel 122 through channel 125 and casing 150 into drain channel 60 so that the pressure in cylinder 94 will be substantially zero and the pressure required to open valve 75 will be determined by the initial tension of spring 50 91, that is, when piston 93 is stalled against the head of cylinder 94.

55 When the tension of spring 154 is between zero and maximum, valve 153 resists the flow of liquid from channel 125 into drain channel 60 and thereby enables gear pump 50 to maintain in cylinder 94 a pressure corresponding to the tension of spring 154 as adjusted.

60 When the tension of spring 154 has been increased to the predetermined maximum, valve 153 prevents liquid from flowing through casing 150 and thereby enables gear pump 50 to maintain in cylinder 94 a pressure equal to the pressure required to open gear pump relief valve 53.

65 The graduations on head 151 indicate various pressures from zero to maximum and are so arranged that the operator, by turning handle 158 until pointer 159 registers with the graduation representing the desired pressure, may cause to be maintained in cylinder 94 any pressure between and including zero and the pressure required to open gear pump relief valve 53.

Operation

If the apparatus is constructed as shown and the free end of control lever 29 is depressed to thereby shift valve 57 toward the left and open groove 66 to groove 70, liquid from gear pump 50 5 will enter cylinder 46 and move piston 47 and slide block 41 toward the left until groove 70 is out of registry with groove 66 as shown in Fig. 2, at which time pump 10 is at a predetermined maximum stroke and discharging liquid into channel 8.

Liquid from pump 10 will flow through channels 9 and 8 to the upper ends of cylinders 5 and 5a and move pistons 4 and 4a, platen 3 and ram 1 downward at high speed, and liquid will flow 15 from tank 15 through channel 14 and surge valve 13 to cylinder 2 and keep it filled.

When platen 3 stalls, pressure will rise in channel 8, extend through channel 18 and shift surge valve 13 to close cylinder 2 to tank 15 and open 20 it to channel 18 and then platen 3 will be urged downward by pump pressure acting upon the combined areas of ram 1 and pistons 4 and 4a.

When pump pressure reaches the maximum determined by the adjustment of selector valve 126, 25 valve 75 will open and permit liquid to enter port 79. If platen 3 stalls suddenly, pump pressure will rise almost instantly but, since pump displacement cannot be reduced instantly due to the inertia of slide block 41 and the resistance 30 offered by choke 95 and throttle 86, pump pressure will momentarily exceed the predetermined maximum value determined by the adjustment of spring 91 and a part of this liquid will flow through choke 114 and channel 113 to the lower 35 end of counterbore 112 and raise piston 111, thereby raising relief valve 105 from seat 108 so that pump 10 can discharge through channels 9, 78 and 107 and valve seat 108 into relief channel 109, it being understood that the pressure 40 required to open relief valve 105 is only a few pounds higher than the pressure required to open valve 75.

At the same time, liquid will flow from port 19 through choke 95 and channel 89 to cylinder 45 44 and move piston 45 and slide block 41 toward the right to reduce pump displacement. The pressure in cylinder 44 will extend through channel 94, choke 101 and channel 97 to the upper part of counterbore 82 but no liquid can escape 50 therefrom for the reason that piston 81 moved upward with valve 75 and closed port 84.

When pump displacement has been reduced enough to cause pump pressure to drop to a value slightly higher than the pressure required to 55 open valve 75, relief valve 105 will close and slide block 43 will continue to move toward the left until pump 10 is delivering just sufficient liquid to maintain the predetermined maximum pressure constant, and then valve 75 will float in 60 an intermediate position with the bottoms of notches 80 and 85 substantially in alignment, respectively, with the adjacent edges of ports 78 and 84, thereby enabling platen 3 to maintain a constant holding pressure upon any work 65 arranged between it and stationary press head 1.

After the holding pressure has been maintained for the desired length of time, the operator may raise the free end of control lever 2, thereby lowering cam 25 and permitting spring 23 to 70 shift rod 21 and follow-up valve 57 toward the right.

Movement of valve 57 toward the right opens drain groove 67 to groove 70 so that liquid can escape from cylinder 46, thereby permitting the 75

pressure in cylinder 44 to move piston 45 and slide block 41 toward the right to further reduce pump displacement with the result that pump pressure drops and permits valve 75 and piston 81 to descend.

5. Piston 81 in descending uncovers port 84 so that liquid from gear pump 51 may flow through channels 52 and 86, port 84, counterbore 82, channel 97, check valve 98 and channel 99 to cylinder 44 and continue the movement of slide block 41 toward the right until valve 57 has stopped and groove 70 has passed out of registry with groove 67 at which time pump 10 is delivering liquid into channel 12.

10. 15. The liquid discharged by pump 10 into channel 12 will flow therethrough and through channel 19 to surge valve 13 and operate it to open cylinder 2 to channel 14. Then the liquid will flow through channels 12 and 11 to the lower ends 20 of cylinders 5 and 5^a and raise pistons 4 and 4^a which will raise platen 3 and ram 1, liquid being 25 expelled from cylinder 2 by ram 1 through surge valve 13 and channel 14 into surge tank 15.

20. 25. When platen 3 approaches the upper limit of its movement, arm 28 will engage collar 33 and raise rod 26 and cam 25 which will move rod 21 and valve 57 toward the left, thereby opening groove 66 to groove 70 so that liquid from gear pump 50 may enter cylinder 46. Since the effective area of piston 47 is greater than the effective pressure area of piston 45 which at this time is also subjected to gear pump pressure, the liquid entering cylinder 46 will move piston 47 and slide block 41 toward the left until the displacement 30 of pump 10 has been reduced to zero at which time upward movement of platen 3 ceases and the free end of lever 29 is in its neutral position.

35. 40. The platen will then remain idle until the free end of lever 29 is again depressed below its neutral position to raise rod 26 and cause cam 25 to shift valve 57 farther toward the left, thereby opening groove 66 to groove 70 so that gear pump liquid may enter cylinder 46 and shift piston 47 and slide block 41 farther toward the left to cause pump 10 to deliver liquid into channel 9 and start another cycle of operation.

45. 50. The invention herein set forth is susceptible of various modifications and adaptations without departing from the scope thereof as hereinafter claimed.

55. The invention is hereby claimed as follows:

1. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a fluid servo-motor for moving said displacement varying means toward zero displacement position, means for supplying motive fluid to said servo-motor to operate the same including a valve urged by pump pressure in a direction to open said valve and admit motive fluid to said servo-motor, means for exerting a force in the opposite direction upon said valve and tending to hold it closed to thereby enable said pump to supply liquid to said actuator at a pressure proportional to said force, and hydraulic means for varying said force.

2. The combination, with a hydraulic actuator, of a variable displacement pump for supplying liquid to said actuator to operate the same, said pump having displacement varying means movable toward and from maximum displacement

position and yieldingly retained in a position corresponding to a predetermined pump displacement, a fluid servo-motor for moving said displacement varying means toward zero displacement position, means for supplying motive fluid to said servo-motor to operate the same including a valve urged by pump pressure in a direction to open said valve and admit motive fluid to said servo-motor, a spring urging said valve in the opposite direction and tending to hold it closed to thereby enable said pump to supply liquid to said actuator at a pressure proportional to the tension of said spring, and hydraulic means for varying the tension of said spring.

3. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a fluid servo-motor for moving said displacement varying means toward zero displacement position, means for supplying motive fluid to said servo-motor to operate the same including a valve urged by pump pressure in a direction to open said valve and admit motive fluid to said servo-motor, means including a piston and a cylinder for urging said valve in the opposite direction and tending to hold it closed, means for supplying motive fluid to said cylinder, resistance means for permitting fluid to escape from the last mentioned means upon the pressure in said cylinder reaching a predetermined maximum to thereby enable said pump to supply liquid to said actuator at a pressure proportional to the pressure in said cylinder, and means for adjusting said resistance means to thereby vary the pressure in said cylinder.

4. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a fluid servo-motor for moving said displacement varying means toward zero displacement position, means for supplying motive fluid to said servo-motor to operate the same including a valve urged by pump pressure in a direction to open said valve and admit motive fluid to said servo-motor, means including a piston and a cylinder for urging said valve in the opposite direction and tending to hold it closed, means for supplying motive fluid to said cylinder to cause said piston to urge said valve toward closed position and thereby enable said pump to supply liquid to said actuator at a pressure proportional to the pressure in said cylinder, and a resistance valve communicating with said cylinder to permit the escape of fluid supplied to said cylinder and thereby enable the last mentioned means to maintain in said cylinder a pressure equal to the pressure required to open said resistance valve.

5. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a fluid servo-motor for moving said displacement varying means toward zero displacement position, means for supplying motive fluid

to said servo-motor to operate the same including a valve urged by pump pressure in a direction to open said valve and admit motive fluid to said servo-motor, means including a piston and a cylinder for urging said valve in the opposite direction and tending to hold it closed, means for supplying motive liquid to said cylinder to cause said piston to urge said valve toward closed position and thereby enable said pump to supply liquid to said actuator at a pressure proportional to the pressure in said cylinder, a plurality of resistance valves, and means for providing communication between said cylinder and the inlet of any one of said resistance valves to thereby enable said liquid supplying means to maintain in said cylinder a pressure equal to the pressure required to open the resistance valve in communication with said cylinder.

6. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a fluid servo-motor for moving said displacement varying means toward zero displacement position, means for supplying motive fluid to said servo-motor to operate the same including a valve urged by pump pressure in a direction to open said valve and admit motive fluid to said servo-motor, a spring urging said valve in the opposite direction and tending to hold it closed to thereby enable said pump to supply liquid to said actuator at a pressure proportional to the tension of said spring, means including a piston and a cylinder for determining the tension of said spring, means for supplying motive liquid to said cylinder, and resistance means communicating with said cylinder and permitting the escape of said motive liquid upon the pressure in said cylinder reaching a predetermined maximum.

7. The combination, with a hydraulic actuator, of a pump for supplying liquid to said actuator to operate the same and having a displacement varying member, a large servo-motor connected to said member, a source of low pressure liquid, means for supplying liquid from said source to said servo-motor to cause it to urge said member in a direction to increase pump displacement, a smaller servo-motor connected to said member for moving it in a direction to decrease pump displacement, means for supplying liquid from said pump to said small servo-motor to operate the same including a valve urged by pump pressure in a direction to open said valve and admit liquid to said small servo-motor, means for exerting a force in the opposite direction upon said valve and tending to hold it closed to thereby enable said pump to supply liquid to said actuator at a pressure proportional to said force, and hydraulic means for varying said force.

8. The combination, with a hydraulic actuator, of a reversible pump for supplying liquid to said actuator to operate the same, said pump having a displacement varying member shiftable in one direction or the other from a neutral position to cause said pump to deliver liquid in one direction or the other, means for shifting said member in a direction to cause said pump to deliver liquid in a given direction and for yieldingly retaining said member in a position corresponding to a predetermined pump displacement, a fluid servo-motor for moving said dis-

placement varying member in the opposite direction, means for supplying liquid from said pump to said servo-motor to operate the same including a control valve urged by pump pressure in a direction to open said valve and admit liquid to said servo-motor, means for exerting a force in the opposite direction upon said valve and tending to hold it closed to thereby enable said pump to supply liquid to said actuator at a pressure proportional to said force, an auxiliary pump, and means for supplying liquid from said auxiliary pump to said servo-motor including a valve movable with said control valve to open said servo-motor to said auxiliary pump when said control valve closes and to close said servo-motor when said control valve opens.

9. The combination, with a hydraulic actuator, of a reversible pump for supplying liquid to said actuator to operate the same, said pump having a displacement varying member shiftable in one direction or the other from a neutral position to cause said pump to deliver liquid in one direction or the other, means for shifting said member in a direction to cause said pump to deliver liquid in a given direction and for yieldingly retaining said member in a position corresponding to a predetermined pump displacement, a fluid servo-motor for moving said displacement varying member in the opposite direction, means for supplying liquid from said pump to said servo-motor, means including a piston and a cylinder for urging said valve in the opposite direction and tending to hold it closed, an auxiliary pump, means for supplying liquid from said auxiliary pump to said cylinder, resistance means for permitting liquid to escape from the last mentioned means upon the pressure in said cylinder reaching a predetermined maximum to thereby enable said reversible pump to supply liquid to said actuator at a pressure proportional to the pressure in said cylinder, means for adjusting said resistance means to thereby vary the pressure in said cylinder, and means for supplying liquid from said auxiliary pump to said servo-motor including a valve movable with said control valve to open said servo-motor to said auxiliary pump when said control valve closes and to close said servo-motor to said auxiliary pump when said control valve opens.

10. The combination, with a hydraulic actuator, of a reversible pump for supplying liquid to said actuator to operate the same, said pump having a displacement varying member shiftable in one direction or the other from a neutral position to cause said pump to deliver liquid in one direction or the other, means for shifting said member in a direction to cause said pump to deliver liquid in a given direction and for yieldingly retaining said member in a position corresponding to a predetermined pump displacement, a fluid servo-motor for moving said displacement varying member in the opposite direction, means for supplying liquid from said pump to said servo-motor to operate the same including a control valve urged by pump pressure in a direction to open said valve and admit liquid to said servo-motor, a spring urging said valve in the opposite direction and tending to hold it closed to thereby enable said pump to supply liquid to said actuator at a pressure proportional to the tension of said spring, an aux- 75

iliary pump, and means for supplying liquid from said auxiliary pump to said servo-motor including a valve movable with said control valve to open said servo-motor to said auxiliary pump when said control valve closes and to close said servo-motor to said auxiliary pump when said control valve opens.

11. The combination, with a hydraulic actuator, of a reversible pump for supplying liquid to said actuator to operate the same, said pump having a displacement varying member shiftable in one direction or the other from a neutral position to cause said pump to deliver liquid in one direction or the other, means for shifting said member in a direction to cause said pump to deliver liquid in a given direction and for yieldingly retaining said member in a position corresponding to a predetermined pump displacement, a fluid servo-motor for moving said displacement varying member in the opposite direction, means for supplying liquid from said pump to said servo-motor to operate the same including a control valve urged by pump pressure in a direction to open said valve and admit liquid to said servo-motor, a spring urging said valve in the opposite direction and tending to hold it closed to thereby enable said pump to supply liquid to said actuator at a pressure proportional to the tension of said spring, means including a piston and a cylinder for determining the tension of said spring, an auxiliary pump, means for supplying liquid from said auxiliary pump to said cylinder, resistance means communicating with said cylinder and permitting the escape of liquid upon the pressure in said cylinder reaching a predetermined maximum, and means for supplying liquid from said auxiliary pump to said servo-motor including a valve movable with said control valve to open said servo-motor to said auxiliary pump when said control valve closes and to close said servo-motor to said auxiliary pump when said control valve opens.

12. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a hydraulic servo-motor for moving said displacement varying means toward zero displacement position, means for supplying liquid from said pump to said servo-motor to operate the same including a valve urged by pump pressure in a direction to open said valve and admit liquid to said servo-motor, means for exerting a force in the opposite direction upon said valve and tending to hold it closed to thereby enable said pump to supply liquid to said actuator at a pressure proportional to said force, and hydraulic means for varying said force.

13. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a hydraulic servo-motor for moving said displacement varying means toward zero displacement position, means for supplying liquid from said pump to said servo-motor to operate the same including a valve urged by pump pressure in a direction to open said valve and admit

liquid to said servo-motor, a spring urging said valve in the opposite direction and tending to hold it closed to thereby enable said pump to supply liquid to said actuator at a pressure proportional to the tension of said spring, and hydraulic means for varying the tension of said spring.

14. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a hydraulic servo-motor for moving said displacement varying means toward zero displacement position, means for supplying liquid from said pump to said servo-motor to operate the same including a valve urged by pump pressure in a direction to open said valve and admit liquid to said servo-motor, means including a piston and a cylinder for urging said valve in the opposite direction and tending to hold it closed, means for supplying motive liquid to said cylinder, resistance means for permitting liquid to escape from the last mentioned means upon the pressure in said cylinder reaching a predetermined maximum to thereby enable said pump to supply liquid to said actuator at a pressure proportional to the pressure in said cylinder, and means for adjusting said resistance means to thereby vary the pressure in said cylinder.

15. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a hydraulic servo-motor for moving said displacement varying means toward zero displacement position, means for supplying liquid from said pump to said servo-motor to operate the same including a valve urged by pump pressure in a direction to open said valve and admit liquid to said servo-motor, means including a piston and a cylinder for urging said valve in the opposite direction and tending to hold it closed, means for supplying motive liquid to said cylinder to cause said piston to urge said valve toward closed position and thereby enable said pump to supply liquid to said actuator at a pressure proportional to the pressure in said cylinder, a plurality of resistance valves, and means for providing communication between said cylinder and the inlet of any one of said resistance valves to thereby enable said liquid supplying means to maintain in said cylinder a pressure equal to the pressure required to open the resistance valve in communication with said cylinder.

16. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a hydraulic servo-motor for moving said displacement varying means toward zero displacement position, means for supplying liquid from said pump to said servo-motor to operate the same including a valve urged by pump pressure in a direction to open said valve and admit liquid to said servo-motor, means including a

- piston and a cylinder for urging said valve in the opposite direction and tending to hold it closed, means for supplying motive liquid to said cylinder to cause said piston to urge said valve toward closed position and thereby enable said pump to supply liquid to said actuator at a pressure proportional to the pressure in said cylinder, and a resistance valve communicating with said cylinder to permit the escape of liquid supplied to said cylinder and thereby enable the last mentioned means to maintain in said cylinder a pressure equal to the pressure required to open said resistance valve.
17. The combination, with a hydraulic actuator, of a variable displacement pump for supplying liquid to said actuator to operate the same, said pump having displacement varying means movable toward and from maximum displacement position and yieldingly retained in a position corresponding to a predetermined pump displacement, a hydraulic servo-motor for moving said displacement varying means toward zero displacement position, means for supplying liquid from said pump to said servo-motor to operate the same including a valve urged by pump pressure in a direction to open said valve and admit liquid to said servo-motor, a spring urging said valve in the opposite direction and tending to hold it closed to thereby enable said pump to supply liquid to said actuator at a pressure proportional to the tension of said spring, means including a piston and a cylinder for determining the tension of said spring, means for supplying motive liquid to said cylinder, and resistance means communicating with said cylinder and permitting the escape of said motive liquid upon the pressure in said cylinder reaching a predetermined maximum.
18. The combination, with a hydraulic actuator, of a power pump for supplying liquid to said actuator to operate the same and having a displacement varying member shiftable in one direction or the other to vary pump displacement and to cause said pump to deliver liquid in one direction or the other, a large servo-motor and a small servo-motor for moving said member in opposite directions, an auxiliary pump, means including a first valve for either connecting said large servo-motor to said auxiliary pump to enable it to move said member in a given direction or connecting it to drain to permit said small servo-motor to move said member in the opposite direction, means for supplying liquid from said power pump to said small servo-motor including a second valve urged by pump pressure in a direction to open said second valve and admit liquid from said power pump to said small servo-motor, means for exerting a force in the opposite direction upon said second valve and tending to hold it closed to thereby enable said power pump to supply liquid to said actuator at a pressure proportional to said force, and means including a third valve for directing liquid from said auxiliary pump to said small servo-motor, said third valve being movable with said second valve and opening and closing oppositely to said second valve.
19. An apparatus as defined in claim 18 wherein said first valve is a follow-up valve and operates to direct liquid to said large servo-motor to cause it to move said displacement varying member in one direction, or to permit liquid to escape from said large servo-motor to thereby permit said small servo-motor to move said member in the opposite direction when both servo-motors are supplied with liquid at the same pressure, or to trap liquid in said large servo-motor and thereby cause said large servo-motor to hold said member stationary until the pressure in said small servo-motor reaches a predetermined maximum.
20. An apparatus as defined in claim 18 including a spring for exerting a force upon said second valve to hold it closed, a piston and a cylinder for controlling the tension of said spring, means for directing liquid from said auxiliary pump to said cylinder at a limited rate, and resistance means for permitting liquid to escape from said last mentioned means upon the pressure in said cylinder reaching a predetermined maximum.

JAMES K. DOUGLAS.
